UNITED STATES PATENT OFFICE.

FRANK J. M. CURRAN, OF GRAND RAPIDS, MICHIGAN.

REFRIGERATOR.

1,380,533.

Specification of Letters Patent. Patented June 7, 1921.

Application filed March 1, 1920. Serial No. 362,329.

To all whom it may concern:

Be it known that I, FRANK J. M. CURRAN, a citizen of the United States of America, residing at Grand Rapids, in the county of Kent and State of Michigan, have invented certain new and useful Improvements in Refrigerators; and I do hereby declare the following to be a full, clear, and exact description of the invention, such as will enable others skilled in the art to which it appertains to make and use the same.

This invention relates to refrigerators. It is a primary object and purpose of my invention to make a refrigerator lining of what is known as L-shape, this lining being designed to be covered with porcelain on its inner sides and form the lining of the provision receiving compartments of the refrigerator, and to construct said lining in a particularly novel and serviceable manner so that the corner where the horizontal and vertical sides of the lining join is fully supported and held securely against any tendency to sag under its own weight. A further object of the invention is to construct a refrigerator in which use is made of said lining and to provide the same with many novel features of construction, particularly in a novel manner of finishing the refrigerator at the door openings and in a novel construction for rendering the doors air tight when closed without the necessity of fitting the doors exceptionally close into the door openings. All of these objects and purposes, together with many others not at this time specifically stated, will appear fully and in detail as understanding of the invention is had from the following description, taken in connection with the accompanying drawings, in which:

Figure 1 is an elevation of the blank from which the back and ends of the lining are made.

Fig. 2 is a perspective view showing said blank bent into form to make said back and ends of the lining.

Fig. 3 is an elevation of a blank used with the blank shown in Fig. 1 to complete the L portion of the lining, except for the bottom and top of the vertical part of said lining.

Fig. 4 shows the blank of Fig. 3 bent to form, looking at the same from the rear.

Fig. 5 is a plan view of the construction shown in Fig. 4.

Fig. 6 is a front elevation of the complete L-shaped lining.

Fig. 7 is a fragmentary vertical section showing the means used to connect the lining with the ice box lining at the upper flue opening which must be made between the ice box and provision chamber of the refrigerator.

Fig. 8 is a plan of a member used to complete the post between the bottom of the lining and the corner of the L.

Fig. 9 is a front elevation thereof.

Fig. 10 is a horizontal section taken through the lower part of a refrigerator equipped with the lining, the method of finishing the refrigerator at the door openings being shown.

Fig. 11 is a vertical section through the bottom of the lining, and

Fig. 12 is a horizontal section illustrating the construction used at the flue opening made in the partition between the ice chamber and the provision compartment below it.

Like reference characters refer to like parts in the different figures of the drawings.

To construct the lining, there is first provided a blank of sheet metal such as shown in Fig. 1, including a relatively wide vertical portion or section 1 from which, at its lower end and at one side a horizontal section 2 projects. Integral with the section 1 is an end portion 3, which it is designed shall be bent forward from the section 1 on the vertical line 4. Similarly a shorter end section 5 is bent forward from the part 2, being bent on the line 6. Each of the ends 3 and 5 are bent inwardly toward each other adjacent their front edges, as indicated at 7, and thence turned outwardly to make vertical flanges 8 positioned at the front edges of said sides 3 and 5.

In connection with the form of sheet metal bent into the shape shown in Fig. 2 and previously described, a second sheet metal form is used, made from a blank of sheet metal as shown in Fig. 3. The plate 9 of sheet metal is slotted from its lower edge and a short distance back of the front edge thereof upwardly for a distance as indicated at 10, leaving two separated parts 11 and 12. The part 12 is turned upwardly to horizontal position, being bent along the line 13, and the form thus made is placed so that the horizontal portion 12 forms a top for the outwardly extending part of the lining and the vertical portion 9 parallels the side 3 and lies directly in front of the free edge

of the back portion 1, being welded thereto. There is also a welding of the rear edge of the portion 12 to the upper edge of the back section 2 and of the free end edge of said part 12 to the upper edge of the end 5, thereby securing the two sheet metal forms permanently together.

The usual flue opening 14 is cut through the top 12 while adjacent the upper edge 10 of the side 9, a flue opening 15 is cut, being practically a depression at the upper edge of said side 9 as shown. The metal around said depression is turned outwardly making a flange 16 bounding the lower side of the 15 depression. Similarly, the metal around the opening 14 is turned upwardly making a continuous flange 17 entirely around the opening.

At the front edge of the side 9, a width 20 of metal equal to the width of the narrow section 11, and in alignment therewith, is bent inwardly toward the opposite inwardly pressed portion 7 of the end 3, as indicated at 18 and then bent forward as shown at 25 19. The section 11 is similarly formed, the formation shown at 18 and 19 extending from the lower end of the section 11 to the upper edge of the side 9. Below the horizontal top 12, a metal reinforce or post is 30 secured to section 11 bent into the form described, said post being made from a strip of metal and formed with a back 21 from which a flange 22 extends forward at one edge. The back 21 is placed against the inwardly 35 bent portion 18 and welded thereto, making a strong supporting post.

The upper end of the lining made by back 1, and sides 3 and 9 is completed by a plate 20 of sheet metal welded into place, 40 it being provided with an upturned flange 20^a at its front. The bottom is made by a plate 23 of metal welded to the lower edges of the back portions 1 and 2 and the lower edges of the ends 3 and 5. Said bottom is 45 formed near its front with an upraised section extending the full width of the bottom and at its front edge a flange 25 is turned down therefrom.

The complete lining is shown in front 50 elevation in Fig. 6. The ice chamber is located above the top 12, its inner side 26 paralleling the side 9 but spaced therefrom as shown in Fig. 7. The flange 16 extends toward side 26 of the ice chamber and in 55 practice is connected thereto by a coupling 27 formed with a flange 28 to bear against the inner side 26 of the ice chamber lining and with a return U-shaped bend 29 which grasps the flange 16 as shown. Any suitable 60 wood insulating member 30 may be disposed between side 9 and side 26 as is usual in refrigerator construction.

The ice chamber also has a lining, the bottom 31 of which has an opening therein 65 coming directly over the opening 14 in the

top 12, said opening in the lining 31 being surrounded by an upturned flange 32. A coupling sleeve 33 has a U-shaped return bend at its upper end which receives the flange 32 as indicated at 34, and is likewise provided with a double bend 35 at its lower end, in one of which the flange 17 seats as shown. The usual wood partition or insulating member 36 is likewise used between top 12 of the L-shaped lining and the 75 bottom 31 of the ice chamber lining.

The lining constructed as described is built into a refrigerator in much the usual manner, there being a frame having vertical side posts 37 and a central post 38 at the 80 front against which the flanges 8 come, being secured thereto by screws or other suitable fastening means. The central post covers the metal reinforce shown at 21 and 22 and also the section 11 bent into the back 85 18 and forwardly extending flange 19. This frame is in turn covered by the outside front casing of the refrigerator included in which are the vertical side members 39 and the central member 40 as shown. The flanges 20^a, 90 12^a and 25 serve to connect the lining at top and bottom to the refrigerator front frame first described and thus firmly secure the lining in place, screws or other suitable fastening means passing through the flanges 95 into horizontal cross members of the frame.

Vertical finishing strips 41 are located one against the part 19 and one against part 22 back of the post 38, being secured in place in any suitable manner. Similar but slightly modified strips 42 are secured back of the posts 37 lying against the inwardly inclined portions 7 of the sides of the lining. This makes a particularly sanitary construction, particularly in connection with the inner 105 porcelain covered sides of the refrigerator lining. The doors 43 closing the openings at the front of the refrigerator are of usual construction but need not be made to closely fit the door openings as the vertical edges 110 of posts 37 and 38, as well as the corresponding cross members at the door openings are equipped with rubber channel shaped strips projecting into the door openings in position to be engaged by the door as shown in 115 Fig. 10, whereby a tight seal against the escape of cold air is made, the rubber yielding readily when the door is closed but always bearing tightly against the door when it is closed.

From the foregoing it is apparent that I have constructed a novel refrigerator lining of the L-shaped type and one in which there is no danger of sagging of the lining at the weak corner thereof. This corner is fully 125 supported against sagging by the vertical part 11 depending therefrom and connected to the bottom of the lining. The raise at 24 in the bottom of the lining leaves the major portion of the lining in a plane be- 130

low the front frame member to which the bottom is attached at the front as shown in Fig. 11, and precludes any water which may be collected on the bottom from running out at the front and over the wood work of the refrigerator. The lining may be readily installed in a refrigerator so as to make an especially sanitary installation, corners where matter might collect being 10 fully covered by the finishing strips. This lining can be manufactured at a low cost as any of its type and is particularly strong and durable. The invention is defined in the appended claims and I consider myself 15 entitled to all constructions which fall within the scope thereof.

I claim:

1. In a refrigerator, a lining comprising an L-shaped back having ends bent forward from the outer vertical edges thereof, a metal member having a vertical slit therein a short distance back of its front edge extending from its bottom edge to a height substantially equal to the horizontal part of the back, the portion of said member back of the slit being bent upwardly and outwardly to substantially horizontal position, said member being secured to the back and shorter end of said first named portion of the lining, a bottom secured at the lower edges of said back and ends, and a top secured in place to complete the lining, leaving the front side open, substantially as described.

2. A construction containing the elements defined in combination in claim 1, combined with a reinforcing member secured to the downwardly extending part of said metal member in front of the slit and disposed 40 between the bottom of the lining and the top of the horizontal portion of the lining, substantially as described.

3. A lining for refrigerators comprising a member of sheet metal having an L-shaped back with ends bent forward from the outer vertical edges thereof, a second member of sheet metal bent to correspond with the L-shaped angle of the back and welded to the back and upper edge of the shorter end, 45 and a supporting post extending downwardly from said second member at the front portion thereof, said lining being completed by a metal bottom welded to the back and ends at the lower edges thereof and a

top welded to the back, the longer end and 55 said second member at the upper edges thereof, substantially as described.

4. A refrigerator lining comprising a receptacle of L-shape open at its front side, and a supporting post disposed at the front 60 thereof between the bottom and the corner of the receptacle, substantially as and for the purposes described.

5. A lining for refrigerators comprising a sheet metal back of L-shape with ends bent 65 forward from the outer edges thereof, a second member formed from a plate of sheet metal slitted a short distance back of its front edge and from its bottom edge upwardly a distance substantially equal to the height of 70 the horizontal portion of the L-shaped back, the part thereof back of the slit being bent upwardly to substantially horizontal, said member being welded to the back and shorter end turned therefrom at the L- 75 shaped angle of the back and upper edge of said end, a bottom of sheet metal welded to the back and said ends at the lower edges thereof, and a top welded to the back, longer side and said second member at the upper 80 edges thereof, substantially as described.

6. A lining for refrigerators as defined in claim 5, in which the part of the second member in front of the slit is bent toward the longer vertical end of the lining for a 85 distance and then forwardly, and a sheet metal reinforcing member comprised of a back and a portion turned forwardly at one edge thereof, secured thereto, said back being welded to the said part of the second 90 member in front of the slit and said forwardly turned portion paralleling the forwardly turned portion of reinforcing member, substantially as described.

7. A refrigerator including a lining of 95 L-shape open at its front side and provided with a post between the bottom of the lining and the corner of the lining above the middle part of the bottom, said post being located at the front of the lining, a 100 frame to which the front edges of the lining are secured, said frame covering the post, and finishing strips located one alongside each side of the post and one against the inner side of each end of the lining back of 105 the frame, substantially as described.

In testimony whereof I affix my signature.
FRANK J. M. CURRAN.
